UNITED STATES PATENT OFFICE.

CLARENCE E. DARROW, OF MIAMI, FLORIDA.

SWIMMING DEVICE.

1,406,940.

Specification of Letters Patent. Patented Feb. 14, 1922.

Application filed June 7, 1921. Serial No. 475,677.

To all whom it may concern:

Be it known that I, CLARENCE E. DARROW, a citizen of the United States, residing at Miami, in the county of Dade and State of

5 Florida, have invented new and useful Improvements in Swimming Devices, of which the following is a specification.

This invention relates to swimming devices and has for an object the provision of 10 a device which is adapted both to pleasure purposes and as a life saving device.

An object of the present invention is the provision of a float or buoyant member which is adapted to support a swimmer and 15 which may be manually driven through the water and steered as desired, the device being especially adapted for surf bathing, as the swimmer may dive through the breakers without swamping the device.

20 Another object is the provision of a device of this character by means of which an additional supporting float may be towed, so as to provide means for supporting an additional person or persons and thus 25 especially adapting the device for the saving of life.

With the above and other objects in view, the invention further includes the following 30 novel features and details of construction, to be hereinafter more fully described, illustrated in the accompanying drawings and pointed out in the appended claims.

In the drawings:—

Figure 1 is a plan view of a swimming 35 device constructed in accordance with the invention.

Figure 2 is an edge view of the same.

Figure 3 is a section on the line 3—3 of 40 Figure 1.

Figure 4 is a side elevation of a modified form of the invention.

Figure 5 is a top plan view of the same.

Figure 6 is a side view of a still further modified form.

45 Figure 7 is an elevation of one type of float which may be towed by the swimming device.

Referring to the drawings in detail, where in like characters of reference denote corresponding parts, reference being had more especially to Figures 1 to 3, the reference character 10 indicates the body of the device which is made up of a pair of boards 11, suitably secured together so as to provide a float or buoyant member. The float is shaped in plan somewhat similar to the

form of a fish and is adapted to provide a support for a swimmer, who will lie flat upon the float with his knees gripping either edge of the same.

60 The opposed faces of the float are provided with grooves which provide a channel 12 for the reception of a drive shaft 13, the latter operating in openings 14 located within the container. The outer or rear end of the shaft 13 has secured thereon a propeller 15, which is adapted to be operated by the swimmer. For this purpose, the inner end of the shaft 13 has secured thereon a beveled pinion 16, which is engaged by and driven 65 by a beveled pinion 17 which is secured upon the inner end of the shaft 18. This shaft and the pinions 16 and 17 are contained within openings or cut out portions provided in the float. The outer end of the shaft 18 is provided with an operating crank 19, so that a person lying upon the float may rotate the shaft 18 so as to operate the drive shaft 13 and the propeller 15 and drive the float through the water. A handle 80 or grip 20 is secured to the float to be grasped by one hand of the swimmer.

85 Pivottally secured beneath the bottom of the float upon a rod or shaft 21 is a rudder 22, the lower end of the rod or shaft 21 being connected to one end of a brace rod 23, the opposite end of which is secured to the float so as to provide a stay for holding the rudder pivot in position. Extending from opposite sides of the rudder beyond the side edges of the float are arms 24, the float being cut away at each side at this point. The feet of the swimmer are placed upon the arms 24 and through this means 90 the direction of travel of the float may be regulated.

95 In Figures 4 and 5 there is illustrated a modified form of the invention in which the float 25 is formed in substantially the same manner as the one previously described, the 100 shape however being slightly different. This float is designed to travel through the water on edge and is provided with a drive shaft 26 which extends rearwardly and downwardly and is provided with a propeller 105 27. An additional shaft 28 extends upwardly and forwardly beyond the end of the float and is provided with a drive shaft 29, the shafts 26 and 28 being in alignment. Secured to each of these shafts is a pinion 110 30, which engages and is driven by a pinion 31 which is secured upon a transversely

arranged shaft 32, the last mentioned shaft being provided with an operating crank 33 so that the shafts 26 and 28 may be manually driven. The rudder in this type of float is 5 formed by a section of the body portion and is indicated at 34, being hinged to the main body portion as shown at 35. This rudder is provided with oppositely extending arms 36, by means of which the rudder 10 is operated after the manner of the rudder 22.

In Figure 6 there is illustrated a still further modified form of the invention and like the form of the device shown in Figures 15 4 and 5 is designed to travel through the water on edge. In this form of the device the drive shaft which is indicated at 37 extends forwardly and is provided with a 20 propeller 38 and at its rear end with a pinion 39. The pinion 40 which is mounted upon the shaft 41 engages the pinion 39 so that when the said shaft 41 is rotated through the medium of the operating crank 42, the propeller will be operated. This 25 form of the device is especially adapted for towing and for this purpose is provided at its forward end with an eye 43, to which may be secured one end of a cable 44. This cable is carried rearwardly and is engaged 30 by a catch 45, so that in towing the cable will trail in the wake of the float. The latter is steered by a rudder 46 which is hinged to the main body as at 47, while arms 48 serve to provide means for operating the 35 rudder.

When the device is used as a life saving device, there is attached to the cable at an appreciable distance from the float, a second float 49, which is provided with flexible 40 grips 50 which are to be grasped by a rescued person or persons so that they may be towed to shore, the towing rope being paid out from the shore during the outward progress of the float. By spacing the float 49 the

proper distance from the towing float, the 45 latter may more easily pass over or through the surf, the swimmer or rider passing through and beyond the influence of the surf before the float 49 reaches the same. This enables the swimmer to obtain sufficient 50 headway to pull the float 49 through the surf. When it is desired to return to shore the cable is released from the catch 49 so that persons at the shore end of the rope may tow in both boats, the towing float 55 returning head on.

The invention is susceptible of various changes in its form, proportions and minor details of construction and the right is here- 60 in reserved to make such changes as prop- erly fall within the scope of the appended claims.

Having described the invention what is claimed is:—

1. A swimming device comprising a pair 65 of flat complementary buoyant members ar- ranged in contact and defining a float, the opposed faces of said members being pro- vided with registering grooves and defining a shaft housing, a shaft rotatable therein, 70 means whereby the shaft may be rotated, a propeller secured upon the shaft and means for steering the float.

2. A swimming device comprising a pair 75 of flat complementary buoyant members ar- ranged in contact and defining a float, the opposed faces of said members being pro- vided with registering grooves and defining a shaft housing, a shaft rotatable therein and extending through one end of the float, 80 means whereby the shaft may be rotated, a propeller secured upon the shaft and a rudder hingedly secured within a cut away corner at one end of the float and forming a 85 continuation of the latter.

In testimony whereof I affix my signature.

CLARENCE E. DARROW.
